TIME-CONTROLLED RADIO PROGRAM PRESELECTOR

Knut J. Magnusson, Princeton, N. J., assignor to
Radio Corporation of America, a corporation
of Delaware

Application May 6, 1943, Serial No. 485,826

17 Claims. (Cl. 250—20)

The present invention relates to a time-controlled radio program preselector which is capable of automatically tuning in certain desired stations at predetermined times.

It is one of the objects of the invention to provide a compact, simple and inexpensive mechanism capable of being housed in the cabinet of a receiver without occupying much additional space.

It is another object of the invention to provide an automatic time-controlled tuning mechanism wherein the clock motor serves as the source of power and a 15 minute cam is used to automatically operate the receiver push-buttons at predetermined times.

It is a further object of the invention to provide a two-station program selector so that the increased cost of the receiver may be reduced to a minimum, but which may be modified in a simple manner to provide a preselector capable of automatically tuning in several stations.

Still another object is to provide control mechanism for a radio receiver provided with a plurality of tuning devices which are operable each to adjust the receiver to a predetermined station, the mechanism comprising a member for selectively actuating the devices, means for effecting movement of the actuating member from an inoperative position to one of a plurality of operative positions, means for moving the actuating member to the inoperative position and for simultaneously storing up energy in the first means, means for releasing the stored-up energy to effect movement of the actuating member, and settable means operative to limit the movement of the actuating member to one of its operative positions to thereby actuate a selected station adjusting device.

A further object of the invention is to provide a plurality of radially-adjustable, uniformly spaced slides or levers circumferentially disposed around the face of a clock mounted on the receiver panel, so arranged that the radial adjustment of each slide or lever determines the particular station to which the receiver is to be tuned or whether the receiver is to be turned off, and each slide or lever, depending upon its angular position, determines the particular time when a particular station is to be tuned in or when the receiver is to be turned off.

The novel features characteristic of my invention are set forth with particularity in the appended claims. The invention itself, however, both as to its construction and mode of operation together with further objects and advantages thereof, will best be understood by reference to the following description taken in connection with the accompanying drawings in which Fig. 1 is a view of the front panel of the receiver, showing the clock face, the circumferentially arranged settable operating levers, and the receiver push-

buttons and control knobs; Fig. 2 is a side view, partly in section, of the time control mechanism embodying the invention; Fig. 3 is a rear view of the apparatus shown in Fig. 2; Figs. 4 to 7 are views showing details of construction of certain elements of the mechanism; Fig. 8 shows schematically the cooperative relation between the various component parts of the mechanism in order to indicate more clearly the operation thereof; Fig. 9 is a circuit showing the connection of the several receiver operating switches; and Fig. 10 shows a modified form of the invention for adapting the time-controlled preselector to a plurality of stations.

Referring first to Fig. 1 the receiver panel is indicated at 10 and an escutcheon plate 11 is attached thereto by means of the four screws 12. A plurality of conventional switch-operating push-buttons 13 extend through an opening 14 at the top of the escutcheon plate. The escutcheon plate is also provided with an opening through which the dial face of an electric clock 15 is viewable. Surrounding the clock dial almost completely except for a small sector below the dial is a series of uniformly spaced radial slots 16 through which extend a plurality of settable or adjustable operating levers 17. Each lever corresponds to a particular 15 minute period, the hours of the day between 6 a. m. and 1 a. m. being marked on the escutcheon adjacent the levers, as shown, for purpose of identification. Since radio receivers are used only infrequently between the hours from 1 to 6 a. m. automatic time tuning for this period has not been provided. However, the space that is provided below the dial by reason of the omission of time tuning for this period is utilized for better styling and the provision of a control knob 18 which enables the user to turn the time tuning "On" or "Off."

Each lever is adjustable in a radial direction, in a manner to be described hereinafter, to one of three positions which correspond respectively to two broadcast stations and the "Off" position of the receiver. Suitable means such as the legends at 19 may be used to identify the several positions of the lever adjustments. By way of example there is shown in Fig. 1 of the drawings the adjustment of the 9:00 a. m. lever in the position corresponding to station WJZ. The 9:15 lever is similarly adjusted, while the 9:30, 9:45 and 10:00 a. m. levers are adjusted respectively to the "Off" position and the WJZ and KYW station positions. With this set-up and provided the time tuning control knob 18 is moved to "On," the receiver will be energized or turned on at 9:00 a. m. and will be adjusted automatically to tune in station WJZ for the next half hour. At 9:30, however, the receiver will be turned off due to the adjustment of the corresponding operating lever to "Off." At 9:45 station WJZ will again be tuned in, and at 10 o'clock station KYW will be

received for the next half hour, after which the receiver will automatically be turned off.

A suitable indicator such as at 20 which shows black for p. m. and white for a. m. through an aperture in the clock dial may be used to apprise the user that the time tuning mechanism is properly synchronized with the electric clock. A control knob 21 acting through suitable means may be employed to adjust the setting of the clock hands and through suitable gearing is adapted to set also the time tuning control mechanism.

Additional controls are provided for operating the receiver in the conventional manner. These are shown below the escutcheon and comprise the power-volume control knob 22', the tone control knob 23', the manual tuning control knob 24' and the range selector 25', if the receiver is of the multi-band type. The speaker grille is indicated at 26'.

The time tuning mechanism will now be described and reference will be made to Figs. 2 and 3. It comprises a frame member 22 of truncated shape which is supported from the rear of the receiver panel by four suitable connecting members 23 which have their outer ends connected to the frame by means of screws 23''. A pair of up-standing brackets 24 are formed in the frame member and serve to support the push-button assembly 25 which is not shown in detail since its construction is not material to the present invention. It need only be stated that the push-buttons 13 are provided each with an operating rod 26 and a part 27 which carries the switch contacts which are moved into operative position upon actuation of the push-rod to connect into circuit one or more pre-tuned circuits, as well known in the art. See for example U. S. Patent No. 2,289,147. The part 27 is provided with a lug 28 by means of which the two central push-rods 26 are actuated by the timing mechanism. Also, the push-rods operate in the conventional manner to release a previously actuated push-rod upon actuation of any one of the other push-rods.

The frame member 22 is provided with a substantially circular portion within which there are formed over the greater portion thereof uniformly spaced radial slots 29 which are aligned with the radial slots 16 formed in the escutcheon plate. Fitted within each slot 29 is an operating lever 17 made of thin sheet metal and having the configuration shown in Fig. 2. In the particular embodiment disclosed 17 such operating levers are required, and being of identical construction they can be produced in large quantities from sheet metal stock by a simple stamping operation at low cost. The portion 30 of each lever is of such configuration that it constitutes at the edge facing toward the front of the receiver a plurality of stops 31, 32 and 33 equal to the number of lever adjustments. A second portion 34 is provided with an equal number of notches 35 with which a spring detent 36 is adapted to engage for maintaining the lever in adjusted position. Each operating lever is also provided with a finger portion 37 which extends through the radial slot 16 in the escutcheon plate and with a cut-out portion 38 which is adapted to engage with a circular laterally extending ridge 39 formed integral with the frame member in such a manner as to serve as a pivotal point about which the operating levers are adapted to swing. The three positions of the operating lever are shown by the dash lines identified with the legends "Off," "WJZ" and "KYW."

A partition plate 40 is supported from the main frame and in the compartment formed by the plate to the right thereof there is housed an electrically driven clock motor 41 which, through suitable gearing, not shown, but represented by the rectangle 42, drives the minute and hour hands of the electric clock. A shaft 43 which is formed as an extension of the clock minute-hand shaft extends rearwardly through the plate 40 and carries at its free end a timing disc 88 and an actuating cam 83 to be described later. A hub 43' is free to rotate on shaft 43 and is axially located between partition plate 40 at its right and a shoulder on the shaft at its left. Solidly mounted on the hub are a gear 46 and a bracket 47. A second, continuously rotated shaft 44 driven from the clock gearing is extended rearwardly through the partition plate which serves as the bearing for this shaft as well as the bearing for the right hand extension of the hub. The hub and bracket 47 are driven from the shaft 44 through the gears 45 and 46 which have such gear ratio that the bracket makes a complete revolution every 24 hours.

Pivotedly mounted at the outer end of the bracket at 47' is a rocker bar 48 which is capable of being rocked in a direction transverse to its direction of rotation. The outer or free end 49 of the rocker bar is adapted to move in the space defined by the lever portions 30 and 34 and to be aligned successively with a different operating lever every 15 minutes. When so aligned the end 49 of the rocker bar is adapted to cooperate with one of the stops 31, 32 or 33, depending upon the particular radial adjustment of the operating lever. The other end of the rocker bar is provided with a pin 50 which rides in a groove 51 formed on the surface of a coupling member 52 which is slidably mounted on the clock driven shaft 43. The coupling member is provided on its surface with a second groove 53 within which there is adapted to ride a pin 54 affixed to a pivoted actuating member 55, now to be described more fully with reference to Figs. 2 and 3.

A rod 56 is horizontally supported at the rear of the frame member by means of clamping brackets 57. The actuating member 55 is pivotally mounted on the rod 56 and comprises the parts 58 and 59 which are connected together by means of screws, rivets or otherwise. The part 58 has an upper U-shaped portion 60, the side arms of which have aligned apertures through which the rod 56 passes. The side arm at the left (Fig. 3) is affixed to the actuating member part 59 and the right side arm extends downwardly and assumes the shape shown in side view in Fig. 2. The lower portion of the part 58 is formed as a rearwardly extending arm 61 which carries at its outer end a roller 62 mounted on a bearing pin 63 affixed to the arm. The outer end of the arm is further provided with an offset portion 64 which extends in the same direction as the roller. The other end of the arm 61 is provided with the inwardly extending pin 54 which as previously described engages the groove 53 of the coupling member.

The other part 59 of the actuating member is formed, as shown in side view in Fig. 2, with an upwardly extended portion 64' and a downwardly and rearwardly extended portion 65. The terminal part of the portion 64' is extended laterally to the left and then forwardly (as viewed in Fig. 3) to form a pawl 66, the operating edge 66' of which is aligned with the depending lug 28 forming a part of one (left) of the two center push-

buttons. A second pawl 67 which is slightly in advance of the pawl 66 extends to the right, being pivoted at 68 and having a part 69 which extends laterally to the left. The operating edge 67' of the pawl 67 is aligned with the lug 28 forming a part of the other (right) of the two center push-buttons. A spring 70 having one end connected to 69 and the other to a lateral extension on the upright 59 serves to maintain the pawl 67 in the position shown in Fig. 2. A stop member 71 disposed in the path of the pawl part 69 is affixed to the frame 22. The arrangement of the parts above described will be understood more clearly from the perspective view of Fig. 4, and the manner of operation of the pawls will be described later.

The lower portion 65 of the actuating member part 59 is formed with a bifurcated part 72 and a hook 73. A tension spring 74 has one end looped over the hook 73 and its other end looped over the end of a shaft 75. The tendency of the spring is to swing the actuating member 55 about its pivotal point (rod 56) in a counterclockwise direction. A lifter bar 76 is provided at its upper end with a bifurcation 77 which is adapted to interlock with the bifurcated part 72 of the actuating member, and at its lower end it is provided with a right-angled cut-out 78, shown in Figs. 6 and 7. A lever 79 is keyed to the shaft 75 and is positioned next adjacent the lifter bar 76, the shaft 75 passing through the cut-out 78. The lever carries at its outer end a pin 80 which also extends through the cut-out. The other end of shaft 75 extends through the panel and the escutcheon, terminating in the time-tuning On-Off control knob 18. Fig. 6 shows the relation of parts when knob 18 is turned to On. When the knob is turned to Off, the lever 79 will be rotated through substantially 90° in a counterclockwise direction (as viewed in Fig. 6) carrying with it the pin 80 which causes the lifter bar 76 to be raised vertically and to be maintained in that position, as shown in Fig. 7. The vertical movement of the lifter bar results in the clockwise rotation of the actuating member against the action of the spring 74. A lug 81 projecting from an edge of the lifter bar 76 is adapted to cooperate with a switch actuator 82, which by reason of the up and down movement of the lifter bar causes respectively the closing and opening of a switch for a purpose to be later described.

The minute-hand shaft 43 as previously stated is extended rearwardly, and at its end there is carried the actuating cam 83 of circular form and provided with four equally spaced lobes 84. A developed view of one of the lobes is shown more clearly in Fig. 8, and is seen to comprise a gradually rising portion 86 which merges into a vertical portion 85, and a horizontal edge portion 87. Mounted behind and movable with the cam is the timing disc 88 provided with four cut-out portions or notches 89 which are spaced 90° apart, a notch being in alignment with the horizontal edge portion 87 of each cam lobe. The minute-hand shaft, cam and timing disc are continuously rotated in unison and make one complete revolution each hour. The cam lobes are so designed that during about nine minutes of rotation of the cam the inclined edge of the lobe will ride under the roller 62 to force the lower end of the actuating member 55 to move rearwardly. As a result, the pawls 66, 67 at the upper end of the actuating member will move forwardly, to the right in Fig. 2. During this interval the actuating member will be moved against the ac-

tion of the spring 74 thereby causing the storing up of energy in the spring. During the continued rotation of the cam, the flat vertical edge 85 of the cam will ride first under the roller 62 to reduce friction and then under the off-set portion 64 until on exactly the quarter hour the abrupt edge of 85 will be cleared by 64. At this point the stored-up energy in the spring will be released to force the actuating member to swing in a counter-clockwise direction. As a result the pawls at the upper end will move rearwardly or to the left, and the arm 61 at the lower end will move to the right. The extent of such movements will be determined by the particular stop 31, 32 or 33 of the operating lever 17 that is effective (as determined by its radial adjustment) to engage the free end 49 of the rocker bar 48, since the lower ends of both the actuating member 55 and the rocker bar 47 are mechanically interconnected by the coupler 52.

It will be observed that for several minutes prior to the tuning operation, during each 15 minute cycle, the pawls 66 and 67 are brought to their extreme forward position (to the right in Fig. 2) away from the lugs 28. This is so because during the last few minutes of the cycle the vertical edge 85 rides under the roller 62 and then under the off-set portion 64, until at the exact instant when tuning is effected the off-set 64 drops off edge 85 and the pawls by action of spring 74 will be forced to move rearwardly or to the left unless prevented from doing so. It will be clear from the description thus far that the extent of the pawl movement is determined by the angular movement of the rocker bar, it being the function of the operating lever, as determined by its radial adjustment, to limit such angular movement.

Now then, with adjustment of a lever 17 to its outer or Off position its stop 33 will be aligned with or in the path of the free end 49 of the rocker bar, so that as off-set 64 drops off edge 85 the angular movement of the rocker bar is only slight, being the clearance that is necessary between 49 and stop 33 for permitting the rocker bar to revolve without interference. Corresponding movement of the pawls is ineffective to contact the lugs 28 to actuate the push-rods.

With adjustment of the lever 17 to its center or WJZ position, as shown in Fig. 2, its stop 32 will be aligned with the free end 49 of the rocker bar, so that as the off-set 64 drops off edge 85 a greater angular movement of the rocker bar takes place. As a result the pawls are permitted to move a correspondingly greater distance rearwardly or to the left which is just sufficient to cause the pawl 67 to push the lug 28 rearwardly for effecting operation of the associated push-rod.

With adjustment of the lever 17 to its inner or KYW position its stop 31 will be aligned with the free end 49 of the rocker bar, so that as the off-set 64 drops off edge 85 a still greater angular movement of the rocker bar takes place, it being observed that the stops 33, 32 and 31 are located at progressively greater distances from the pivotal point 38. As a result the pawls are permitted in this instance to move a still greater distance rearwardly or to the left. During the initial movement of the pawls, that is through the same angular movement as in the previous case, they will both move in unison. However, as the top of the pawl carrier 59 continues to the left (Fig. 2) the pawl 67 is swung counterclockwise around its pivot 68 and lets go of its aligned lug 28 on

the push-rod 26 for station WJZ at about the same time that the operating edge 66' of pawl 66 coacts with its aligned lug 28 on the push-rod for station KYW. The push-rod for station WJZ is then released while that for station KYW becomes latched in.

Also pivotally mounted on the supporting rod 56 are a pair of locking levers 90 and 91 which are adapted to swing in the same direction as the actuating member and which are adapted also to move with respect to one another. As more clearly shown in Fig. 5 the lower ends of the locking levers have laterally bent portions 92 each provided with three notches 93 to correspond with the number of positions of adjustment of the operating levers. The lever 91 is provided with a part 94 bent at right angles thereto and serves to cooperate with an insulating stud 95 carried by the movable blade of a switch 95. A spring 96 tends to urge both locking levers rearwardly, and the spring 97 tends to urge the locking lever 91 in a forward direction to a position whereby the notches in both levers will be in registry. Depending upon the position of the actuating member 55, as determined by which operating lever-stop the rocker bar is engaged with, the timing disc 88 will ride through one or the other of the notches of the locking levers. At the instant when the actuating member is released to operate one or the other of the two center push-buttons, the timing disc will have been rotated to a position such that one of its notches will be in the path of the laterally bent portions of the locking levers to permit them to return to a normal position by action of the return spring 96. When an operating lever is adjusted to Off, the position of the actuating member will be as shown by the dash line in Fig. 8, and the locking lever 91 will be rocked to the left by the spring 96 so that the right hand notch 93 will engage with the timing disc 88 to lock the lever 91 in this position for the next 15 minutes. In this locked position the part 94 will coact with the stud 95 to open the switch 95 in the receiver power supply circuit.

In order to obtain a clearer understanding of the invention, the operation of the device above described will be reviewed with reference to Fig. 8 which shows schematically and in simplified form the essential elements disclosed in the other figures, corresponding parts having been indicated by the same reference character.

Let it be assumed that cam 83 has just completed one-quarter of its revolution and that it rotates in a direction such that the cam lobe 84 is moved downwardly in the direction of the arrow. During approximately 9 minutes of this quarter revolution or 15 minute period, the cam lobe 84 forces the actuating member 55 to swing clockwise to the position shown by the dash line. This action also swings the top end 49 of the rocker bar or rotary selector arm 48 to the right into the open space between portions 30 and 34 of the selector levers 17 where it is free to rotate. At the same time spring 74 is stretched or put under tension and stores up enough energy to operate the push button switches. When cam 83 has advanced far enough, that is to the position shown in the figure, the part 64 drops off the cam lobe at the edge 81 and spring 74 forces member 55 to swing counter-clockwise a distance determined by the middle stop 32 of station selector lever 17. As shown, the station selector lever is set for station WJZ and the pawl end 66, 67 of

the actuating member has pushed the corresponding button as a result of its engagement with the lug 28.

If the selector 17 had been set for station KYW, 5 the pawl end of the actuating member would have actuated the corresponding button, travel of the actuating member being determined by the rotary selector coming up against the stop 31 on the selector lever. If the station selector had been set to the Off position the rotary selector 48 would abut against stop 33 and the actuating member 55 would assume the dash line position thereby preventing its upper end from pushing any station button. A few seconds later the lever 91 10 swings to the left thus opening switch 95 which shuts off the radio.

Levers 90 and 91 are normally locked in any one of three positions by means of locking and timing disc 88 and are free to move only at the 15 end of each 15 minute period when a notch in disc 88 registers with the formed up ends 92 of levers 90, 91. These notches must be wide enough to permit levers 90, 91 to swing freely to the right and turn the radio on when forced to do so by the actuating member swinging counter-clockwise (in Fig. 8 when the lower part of 55 moves to the right). This means, however, that when the end 64 of the actuating member is still on top of cam lobe 84, lever 91 would swing back and momentarily turn the radio off until cam 83 was in a position to again release the arm 64. To prevent this, the secondary locking lever 90 is provided. This is similar to lever 91 but somewhat shorter and connected thereto by the spring 97. Lever 91 is therefore free to swing counter-clockwise (to the right) with actuating member 55, but can not move clockwise (to the left) until lever 90 registers with a notch in timing disc 88.

In order to permit relative adjustment between 20 actuating member 55 and levers 90, 91 (which adjustment is necessary for properly synchronizing the movement of the latter with that of the timing disc 88), the member 55 is provided with a part 88 bent at right angles and disposed to the rear of and in parallel relation with the part 94 of lever 91 (Figs. 2 and 3). Threaded through part 25 98 is an adjusting screw 99 against the end of which part 94 is forced to abut by action of the spring 96.

The electrical connections of the several 30 switches previously described are shown in Fig. 9. 100 is the main on-off switch for the receiver which is controlled by the knob 22' on the front panel. 101 is the time tuning switch actuated by the member 82 under the control of the lifter bar 76 which in turn is controlled from the front panel by the knob 18. The switches 100 and 101 are connected in series in the power line between the source and the receiver 102. Connected in shunt with time tuning switch 101 is the switch 95 which is under control of the timing mechanism.

In operation of the receiver the main switch 100 is turned on. When time tuning is not desired, actuation of the control knob 18 to Off will result in the closure of switch 101 so that whether switch 95 happens to be open or closed, the energization of the receiver will be entirely under the control of switch 100. When time tuning is desired, actuation of knob 18 to On will result in the opening of switch 101, so that energization of the receiver will be entirely under the control of the switch 95.

While in the modification above described the

time tuning feature has been applied to select only two stations for reasons already stated, by simple modification the apparatus may be adapted to automatically tune in a plurality of stations at predetermined times. This is shown in Fig. 10. The locking levers 90, 91 are replaced by the laterally movable rack member 91' which is adapted to rotate the pinion 103 affixed to a shaft 103'. Mounted on the pinion shaft for movement therewith are two switch wafers 104, 105. Actually the wafers and the pinion are assembled side by side, but in order to clarify the construction the several parts are shown in an exploded view. Each wafer is provided with a conducting peripheral or ring portion 106, 107 with which there is in continual contact a brush collector O, O', respectively. On the respective conducting rings there is formed a switch blade 108, 109. The switch blade 108 is adapted to selectively contact with one of a plurality of stationary contacts A, B . . . E circumferentially arranged around the wafer 104, and the switch blade 109 is adapted to selectively contact with one of a plurality of stationary contacts A', B' . . . E' circumferentially arranged around the wafer 105. It will be noted that the several pairs of stationary contacts A, A'; B, B'; etc. and the switch blades 108, 109 are phased, as illustrated.

The contacts A to E have each connected thereto one terminal of a plurality of tuning inductances A₁ to E₁, preferably permeability tuned or iron core coils, the opposite ends of the coils being connected to ground. The contacts A' to E' have each connected thereto one terminal of a plurality of trimmer condensers A_c to E_c, the opposite ends being connected to ground. The brush collectors O and O' have connected thereto the conductors 110 and 111 which lead to the receiver proper in a manner well-known in push-button receivers of the electrical type. For example, the collectors O and O' and the leads 110 and 111 may correspond to the fixed contacts 55 and 63 and the leads connected thereto, as disclosed in Fig. 1 of Chittick et al. Patent No. 2,209,959. In the shown position of the switch wafers the receiver will be tuned to station A. In the off position of the switch, the contacts 108 and 109 will contact with the brush collectors O and O' thereby disconnecting the several pretuned circuits from the receiver.

On the under surface of the rack member there are provided cut-out portions or notches 93'. Five of the notches correspond to the number of stations to be selected, in this case the stations being A to E, and the sixth notch serves to turn the receiver off. As in the first modification the timing disc 88 is adapted to engage one of the notches 93' depending upon the position of the actuating member 55, the engaged notch in turn determining the lateral movement of the rack 91' and the angular movement of the switch contacts 108, 109. It will be understood of course that in this modification also the operating selector levers 17 will be provided with as many stops as there are stations to be selected and in addition an Off stop. In operation the actuating member 55 will assume an angular position about its pivotal point 56 corresponding to the adjustment of the selector levers. This angular position will also determine the extent of lateral movement of the rack, and incidentally the angular rotation of pinion 103 and switch wafers 104, 105 for selecting the appropriate pretuned circuit elements for connection to the receiver.

While I have shown and described certain pre-

ferred embodiments of my invention, it will be understood that various modifications and changes will occur to those skilled in the art without departing from the spirit and scope of this invention. I therefore contemplate by the appended claims to cover any such modifications as fall within the true spirit and scope of my invention.

What I claim is:

1. Control mechanism for a radio receiver provided with a plurality of push-buttons which are operable each to render the receiver selective to a predetermined station, comprising a member for selectively actuating said push-buttons, means for effecting movement of said actuating member from an inoperative position to one of a plurality of operative positions, means for moving the actuating member to the inoperative position and for simultaneously storing up energy in the first means, means for releasing the stored-up energy to effect movement of the actuating member, and settable means operative to limit the movement of the actuating member to one of its operative positions to thereby actuate a selected one of said push-buttons.

2. Control mechanism for a radio receiver provided with a plurality of push-buttons which are operable each to render the receiver selective to a predetermined station, comprising a member for selectively actuating said push-buttons, spring means for effecting movement of said actuating member from an inoperative position to one of a plurality of operative positions, means for moving the actuating member to the inoperative position against the action of the spring means causing potential energy to be stored-up therein, means for releasing the stored-up energy of the spring means to effect movement of the actuating member, and settable means operative to limit the movement of the actuating member to one of its operative positions to thereby actuate a selected one of said push-buttons.

3. Control mechanism for a radio receiver provided with a plurality of push-buttons which are operable each to render the receiver selective to a predetermined station, comprising a member for selectively actuating said push-buttons, means for effecting movement of said actuating member from an inoperative position to one of a plurality of operative positions, means for moving the actuating member to the inoperative position and for simultaneously storing up energy in the first means, means for releasing the stored-up energy to effect movement of the actuating member, and manually settable means provided with a plurality of stops for limiting the movement of the actuating member to one of its operative positions to thereby actuate a selected one of said push-buttons.

4. Control mechanism for a radio receiver provided with a plurality of push-buttons which are operable each to render the receiver selective to a predetermined station, comprising a member for selectively actuating said push-buttons, means for effecting movement of said actuating member from an inoperative position to one of a plurality of operative positions, time-controlled means for periodically moving the actuating member to the inoperative position and for simultaneously storing up energy in the first means, means for periodically releasing the stored-up energy to effect movement of the actuating member, and settable means operative to limit the movement of the actuating member to one of its operative positions to thereby actu-

75

ate a selected one of said push-buttons at a pre-determined time.

5. Time clock controlled mechanism for a radio receiver provided with a plurality of push-buttons which are operable each to render the receiver selective to a predetermined station, comprising a member for selectively actuating said push-buttons, means for effecting movement of said actuating member from an inoperative position to one of a plurality of operative positions, clock-controlled means for periodically moving the actuating member to the inoperative position and for simultaneously storing up energy in the first means, means for periodically releasing the stored-up energy to effect movement of the actuating member, and manually settable means provided with a plurality of stops for limiting the movement of the actuating member to one of its operative positions to thereby actuate a selected one of said push-buttons, one of said stops serving to maintain the actuating member in its inoperative position.

6. Control mechanism for a radio receiver provided with a plurality of push-buttons which are operable to render the receiver selective to predetermined stations, comprising an actuating member for selectively actuating said push-buttons, spring means for effecting movement of said actuating member from an inoperative position to one of a plurality of operative positions, continuously operated means for periodically effecting movement of the actuating member to the inoperative position against the action of the spring means, means for releasing the actuating member at predetermined times, and manually settable means provided with a plurality of stops corresponding in number to the operative positions of the actuating member for limiting the movement of the actuating member to one of its operative positions depending upon the adjustment of the settable means.

7. Control mechanism for a radio receiver provided with a plurality of push-buttons which are operable to render the receiver selective to predetermined stations, comprising an actuating member pivoted at an intermediate point, one end of said member being adapted to selectively actuate said push-buttons, spring means for effecting movement of said actuating member about its pivotal point from an inoperative position to one of a plurality of operative positions, cam means cooperating with the other end of said actuating member for effecting movement thereof to the inoperative position against the action of the spring means and for releasing the actuating member, and manually settable means provided with a plurality of stops corresponding in number to the operative positions of the actuating member for limiting the movement of the actuating member to one of its operative positions depending upon the adjustment of the settable means.

8. Control mechanism for a radio receiver provided with a plurality of push-buttons which are operable to render the receiver selective to predetermined stations, comprising an actuating member pivotally mounted at an intermediate point, means at one end of said member for selectively actuating said push-buttons, spring means for effecting movement of said actuating member about its pivotal point from an inoperative position to one of a plurality of operative positions, cam means cooperating with the other end of said actuating member for effecting movement of said member to the inoperative position

against the action of the spring means and for releasing the actuating member, a rocker bar, means for mechanically coupling said other end of the actuating member to one end of the rocker bar whereby the movement of the former is transmitted to the latter, and manually settable means provided with a plurality of stops corresponding in number to the operative positions of the actuating member, said stops being adapted to cooperate with the other end of the rocker bar to limit its movement and concomitantly that of the actuating member to one of its operative positions depending upon the adjustment of the settable means.

9. Time clock controlled mechanism for a radio receiver provided with a plurality of push-buttons which are operable to render the receiver selective to predetermined stations, comprising an actuating member pivotally mounted at an intermediate point, means at one end of said member for selectively actuating said push-buttons, spring means for effecting movement of said actuating member about its pivotal point from an inoperative position to one of a plurality of operative positions, a clock-driven shaft, cam means movable with said shaft cooperating with the other end of said actuating member for effecting the periodic movement of said member to its inoperative position against the action of the spring means and for releasing the actuating member at predetermined times, a rocker bar continuously rotated from the clock-driven shaft, means for mechanically coupling said other end of the actuating member to one end of the rocker bar whereby movement of the former is transmitted to the latter, and a plurality of manually adjustable stations and time determining levers, each provided with a plurality of stops corresponding in number to the operative positions of the actuating member, said stops being adapted to cooperate with the other end of the rocker bar to limit its movement and concomitantly that of the actuating member to one of its operative positions depending upon the adjustment of said levers.

10. The combination with a radio receiver having a plurality of push-buttons operable each to render the receiver selective to a predetermined station, of time clock controlled mechanism for automatically tuning in said stations at predetermined times, said mechanism comprising a member for selectively actuating said push-buttons, means for effecting movement of said actuating member from an inoperative position to one of a plurality of operative positions, each of the latter positions determining the station to be tuned in, clock-controlled means for periodically moving the actuating member to the inoperative position and for simultaneously storing up energy in the first means, means for periodically releasing the stored-up energy to effect movement of the actuating member, and manually settable means provided with a plurality of stops for limiting the movement of the actuating member to one of its operative positions to thereby actuate the corresponding one of said push-buttons.

11. The combination with a radio receiver having a plurality of push-buttons operable each to render the receiver selective to a predetermined station, of time clock controlled mechanism for automatically tuning in said stations at predetermined times, said mechanism comprising a frame having an annular portion within which there are formed a plurality of radially extend-

ing key-ways, a plurality of operating keys each pivotally mounted within one of said key-ways and each having as many positions of adjustment as there are stations to be automatically tuned in, a clock-driven shaft extending transversely of the frame and arranged centrally with respect to the operating keys, a member pivotally supported from said frame for selectively actuating said push-buttons, means for effecting movement of said actuating member from an inoperative position to one of a plurality of operative positions, cam means movable with the shaft for periodically moving the actuating member to the inoperative position and for simultaneously storing up energy in the first means, means for periodically releasing the stored-up energy to effect movement of the actuating member, a rocker bar continuously rotated by the shaft arranged to move in a direction transversely to its direction of rotation, said rocker bar having a free end which is adapted to successively cooperate with the operating keys, and mechanical coupling means between the other end of the rocker bar and the actuating member, the arrangement being such that the adjustment of the operating key determines the extent of transverse movement of the rocker bar and comitantly the movement of the actuating member to a corresponding position for selectively operating the push-buttons.

12. The combination with a radio receiver having a plurality of push-buttons operable each to render the receiver selective to a predetermined station, of time clock controlled mechanism for automatically tuning in said stations at predetermined times, said mechanism comprising a frame having a circular portion which is provided with uniformly spaced radial slots, a plurality of operating levers each pivotally supported within one of said slots and each capable of a plurality of adjustments in a radial direction, each operating lever having a portion of such configuration that it constitutes a plurality of stops equal to the number of lever adjustments, a member for selectively actuating the push-buttons, means for effecting movement of said actuating member from a neutral position to one of a plurality of operative positions, and clock-controlled means adapted to cooperate successively with one of the stops of each operating lever for periodically limiting the movement of the actuating member to one of its operative positions to thereby actuate the push-buttons.

13. The combination with a radio receiver having a plurality of push-buttons operable each to render the receiver selective to a predetermined station, of time clock controlled mechanism for automatically tuning in said stations at predetermined times, said mechanism comprising a frame having a circular portion which is provided with uniformly spaced radial slots, a plurality of operating levers each pivotally supported within one of said slots and each capable of a plurality of adjustments in a radial direction, each operating lever having a portion of such configuration that it constitutes a plurality of stops equal to the number of lever adjustments, a second portion provided with an equal number of notches with which a spring detent is adapted to engage for maintaining the lever in adjusted position, and a finger portion, a member for selectively actuating the push-buttons, means for effecting movement of said actuating member from a neutral position to one of a plurality of operative positions, and clock-controlled means

adapted to cooperate successively with one of the stops of each operating lever for periodically limiting the movement of the actuating member to one of its operative positions to thereby actuate the push-buttons.

14. The combination defined in claim 13, wherein an escutcheon plate is mounted on the receiver panel and is provided with radial slots aligned with those of the frame and through which the finger portions of the operating levers extend.

15. The combination with a radio receiver having a plurality of push-buttons operable each to render the receiver selective to a predetermined station, of time clock controlled mechanism for automatically tuning in said stations at predetermined times, said mechanism comprising a frame having a circular portion which is provided with uniformly spaced radial slots, a plurality of operating levers each pivotally supported within one of said slots and each capable of a plurality of adjustments in a radial direction which determine the particular station to which the receiver is to be tuned or whether the receiver is to be turned off, and each lever depending upon its radial position determining the particular time when the particular station is to be tuned in or when the receiver is to be turned off, a member for selectively actuating the push-buttons, means for effecting movement of said actuating member from an inoperative position to one of a plurality of operative positions, and clock-controlled means adapted to cooperate successively with said operating levers for periodically limiting the movement of the actuating member to its inoperative position or to one of its operative positions depending upon the adjustment of successive operating levers.

16. Time clock controlled mechanism for attachment to a radio receiver having a plurality of push-buttons operable each to render the receiver selective to a predetermined station whereby said stations are automatically tuned in at predetermined times, said mechanism comprising a frame having a circular portion which is provided with uniformly spaced radial slots, a plurality of operating levers each pivotally supported within one of said slots and each capable of a plurality of adjustments in a radial direction, each operating lever having a finger portion and a portion of such configuration that it constitutes a plurality of stops equal to the number of lever adjustments, a member for selectively actuating the push-buttons, means for effecting movement of said actuating member from a neutral position to one of a plurality of operative positions, clock-controlled means adapted to cooperate successively with one of the stops of each operating lever for periodically limiting the movement of the actuating member to one of its operative positions to thereby actuate the push-buttons, an electric clock centrally supported on the frame and having its dial exposed through an aperture in the receiver panel, and an escutcheon plate surrounding the clock dial provided with radial slots through which extend the finger portions of the operating levers.

17. Time clock controlled mechanism in accordance with the invention defined in claim 16 wherein means are provided for causing the operation of the receiver under the control of the timing mechanism to be ineffective, said means being controlled from the receiver panel.
